UNITED STATES PATENT OFFICE.

WILLIAM M. SCOTT, OF TREDYFFRIN TOWNSHIP, CHESTER COUNTY, PENNSYLVANIA.

SWITCHING APPARATUS.

Application filed February 17, 1923. Serial No. 619,586.

My invention relates to electrical switch or circuit breaker structure for controlling or protecting electric circuits for carrying current for power, lighting or other purposes.

In accordance with my invention, a switch or circuit breaker structure is provided with means for locking it in normal, generally circuit closing position, and is disposed within a housing upon whose movement or upon movement of a door or wall of which the switch or circuit breaker structure is tripped and moves to abnormal, generally open circuit, position, from which it cannot be returned to or latched in normal position until the housing, or a door or wall thereof, is returned to closed or normal position.

Further in accordance with my invention, the switch or circuit breaker structure may be manually tripped from the exterior of the housing by a member sliding upon or through the actuating mechanism without movement of the actuating mechanism with or in the direction of the tripping member.

My invention resides in features of structure and combination hereinafter described and claimed.

For an illustration of one of the various forms my invention may take, reference is to be had to the accompanying drawings, in which:

Fig. 1 is a side elevational view, partly in section, of structure embodying my invention.

Fig. 2 is a front elevational view of structure shown in Fig. 1, with part of the housing broken away.

Fig. 3 is a fragmentary side elevational view, partly in section, on enlarged scale, of part of the structure illustrated in Fig. 1.

Figs. 4 and 5 are side and top plan views, respectively of a bracket member involved in the structure of Fig. 1.

Figs. 6 and 7 are side and front elevational views, respectively, of a pivoted control member of the structure illustrated in Fig. 3.

Figs. 8 and 9 are front and side elevations, respectively, of a member involved in the structure of Fig. 3.

Fig. 10 is a side elevational view, partly in section, of a modification of the structure of Fig. 3.

Fig. 11 is a fragmentary front elevational view of the actuating mechanism.

Referring to the drawings, upon a base 1, of suitable insulating material, are secured two switch or circuit breaker mechanisms A and B, Fig. 2, the description of the parts 60 of one of which will suffice for both.

The two circuit breaker arms, A and B, form a so-called "double arm" circuit breaker, the two arms or poles of which are independently operable to normal or closed position, both connected in series in the same circuit, preferably one arm in each side of the circuit, with automatic tripping mechanism ensuring the tripping of an arm first closed if there obtains an overload or other abnormal electrical condition upon attempt to close the other arm, in general the same as described in my prior Patent 1,389,-996.

Each arm or circuit breaker comprises the main terminals 2 and 3, adapted to be connected or bridged by the laminated bridging contact member 4 carried by an arm 5 pivoted to the bracket 6 at 7. Pivoted to the arm 5 at 8 is a toggle link or member 9 pivoted at 10 to the toggle link 11 pivoted at 12 to the bracket 6 on base 1. The member 9 may, as indicated in Fig. 2, take the form of plates joined by the plate 13, which carries a pin or roller 14. The member 9 carries a pin or roller 15, which is engaged by the hook latch 16 pivoted to the housing 6 at 7, and having the tail 17. Pivoted concentrically with the latch 16 is the latch actuator or bar 18 extending in front of both arms of the breaker mechanism and adapted to engage and actuate the tails 17 of the latches 16 to release the members 9.

In series with the bridging member 4 is the winding or coil 19 of an overload tripping magnet whose armature 20, pivoted at 21, carries an upstanding arm 22 adapted to engage the tripper tail 18^a, which may be attached to and rotates the latch actuator bar 18 in clockwise direction, as viewed in Fig. 1, to effect actuation of the latch 16 and tripping of the breaker mechanism. Co-acting with the armature 20 may be a start-delaying device 23 of the sucker type.

The base 1 is hung upon and hinged to the metal box or housing 24 by suitable hook structure 25, or equivalent, the box 24 being secured to any suitable support by screws 26, whereby the base 1 and the circuit breaker structure carried thereby are carried and supported by the box 24.

Through suitable conduits or pipes 27 com-

municating with the interior of the box 24 extend the insulated circuit supply conductors 28 and 29, connected, respectively, to the studs 30 and 31, extending through the base 1 and connected, respectively, to the upper terminals 2 of the breaker arms A and B.

One terminal of each of the magnet coils 19 connects with the lower main terminal 3, and the other terminals of the coils 19 connect, respectively, with the studs 32 and 33, with which connect, respectively, the consumption circuit conductors 34 and 35, extending through the lower pipe or conduit 27.

Hung upon or carried by the rear box or housing 24 by hook hinges 25^a is the front box or housing H, which encloses the hereinbefore described circuit breaker mechanism. The housing H may be of sheet metal and may be locked in the closed position indicated in Fig. 1 by any suitable means. For this purpose there are provided upon the bottom of the box 24 the lugs 36, in which there is pivoted at 37 the hasp 38, adapted to engage in a notch 39 in the link 40, pivoted to the bottom of the housing H at 41 in the lugs 42.

The parts are shown in dotted lines in the unlocked position. By rotating the link 40 in counter-clockwise direction, as viewed in Fig. 1, about its pivot 41, it takes the full line position indicated. The hasp 38 and link 40 form in effect a toggle which, in the full line position indicated in Fig. 1, is overtravelled, thereby holding the housing H locked to the housing 24, and by the lug 41^a secured to the housing H also holding and locking the base 1 to housing 24. The free end of the link 40 is adapted to enter between the lugs 43 upon the bottom of the base H, these lugs having aligned holes, and the link 40 having a hole 44 which comes into register with them, and through the holes when in register may be inserted the hasp 43^a of a padlock L which prevents unlocking the housing H from the housing 24.

Secured upon the inner side of the front wall of the housing H is a bracket 45, in which is pivoted the hollow or tubular shaft 46 having the bore or hole 47. The shaft 46 extends to the exterior of the housing H, and there is secured to it, as by pin 48, the operating lever or handle 49. Secured upon the shaft 46 within the housing H, but carried thereby on the bracket 45, is the actuating member 50, whose side edges, as indicated in Figs. 1 and 11, are adapted to engage and depress the pins or rollers 14 on the toggle members 9.

With both arms of the mechanism in open circuit position, by rotating the operating lever 49 in one direction the actuating member 50 will engage and depress one of the pins 14, thereby extending the associated

toggle and moving the movable contact member 4 to circuit closing position, in which it is latched by engagement of the latch 16 with the roller 15. Corresponding movement of the lever 49 in opposite direction effects a similar closure of the other arm. A suitable spring, not shown, biases the member 50 to mid or neutral position, indicated in Figs. 1 and 11. As described, and as shown in Fig. 11, the actuating member 50 is detached from the circuit breaker structure.

Pivoted to the inner end of the bracket 45 at 45^a (which happens to be about concentric with 10, as shown in Fig. 1, but has no connection thereto) is the tripping lever 51, a spring 52, under tension, normally holding the lever in the position indicated in Fig. 1.

Structure of the character above described, involving the actuating member 50 and the tripping member 51 carried by the housing H and in detached relation, respectively, to the members 14, 14 and 18, is disclosed in my prior Letters Patent No. 1,515,759, November 18, 1924.

Extending through the hole or bore 47 of the shaft 46 is the rod or plunger 53 having at its outer end the head or button 54, to which is applied the hand or thumb of the operator to push the plunger 53 from right towards the left, Fig. 1, thereby rotating the tripping lever 51 about its pivot in opposition to spring 52, the lower end of the lever 51 engaging and actuating the tripper bar 18, which then actuates the tails 17 of the latches 16 of both arms, tripping both simultaneously. By the construction just described, the actuating mechanism or member 50 is not moved inwardly with the tripping plunger or rod 53, the actuating member 50 being confined against motion longitudinally of its axis of rotation, and therefore confined substantially to a given plane of rotation.

Carried upon the base 1 is the outstanding bracket 55, to which is pivoted at 56 the vertically extending lever 57, to which is attached at its upper end a pin 59, to which is attached one end of the spring 60, whose other end is attached at 64 to the bracket 55, the spring 60 tending to pull the upper end of the lever 57 toward the left, Fig. 3. Such movement is prevented by the member 62, which may take the form of a screw 12 threaded through the upstanding bracket 63, whose base 64 is secured to a side wall of the housing H. The screw 62 forms an adjustable abutment against which abuts the lower end 57^a of the lever 57. The screw 62 may be locked in position to which adjusted by the lock nut 65.

The upper end of the lever 57 is disposed adjacent the tripper bar 18, whereby, when the housing H is swung upon its hook piv-

ots 25^a away from the base 1, the abutment 62 is withdrawn away from the lower end of the lever 57, whose upper end is then moved toward the left, Fig. 3, by the spring 60, and caused to actuate the tripper bar 18 for tripping such one or more of the arms A or B which may be in circuit closing position. In returning the support or housing H to operative relation with respect to the base 1 and the switching mechanism, the abutment 62 engages the lever 57, moving it upon its pivot 56 in opposition to spring 60 to position preventing actuation of the restraining means. The members 38 and 40, carried, respectively, by the front and rear housings H and 24, detachably engage each other and constitute a force-multiplying device easily manually operable to apply force to the housing or support H to move it to its final operative position in opposition to spring 60, and when the members 38 and 40 are in the locking position indicated in Fig. 1, they hold the housing or support H in its operative position in opposition to spring 60. Upon release of the members 38 and 40, as by carrying the toggle constituted by them to undertravelled position, the spring 60 tends to swing the housing H away from the base 1 and to move the lever 57 in the direction in which it moves to effect tripping of the circuit breaker mechanism by actuation of its restraining means.

From the structure described, it follows that upon removal of the housing H the circuit breaker mechanism within it is automatically tripped, and so long as the housing is so removed from the normal or closed position indicated in Fig. 1, the spring 60 will hold the upper end of the lever 57 against the tripper bar 18, which in turn holds the latches 16 in unlocked position, whereby neither circuit breaker arm can be latched closed so long as the housing H is not in its normal closed position.

Similar structure is shown in Fig. 10. In this case, however, the abutment 62 is carried by the door or movable wall D of the housing H and pivoted thereto at d, whereby if the wall or door is opened or removed, either or both breakers will be tripped, according as either or both were in circuit closing position, and neither can be locked in circuit closing position until the wall or door D is returned to such position as to return the lever 57, in opposition to spring 60, to position leaving the tripper bar 18 free. The door or movable wall D may carry, as shown the actuating and tripping mechanism, comprising members 50 and 51, or their equivalents, in an arrangement similar to that indicated in Fig. 1 wherein the actuating member 50 and tripping member 51 are in detached relation to members 14, 14 and 18, respectively, and

are carried by a wall of the movable housing H.

Some of the features of my present invention are in their broader aspects claimed in my co-pending applications serially numbered 427,979 and 447,114, filed, respectively, December 3, 1920 and February 23, 1921, upon which have issued Letters Patent No. 1,505,107 and No. 1,515,759, respectively.

What I claim is:

1. The combination with switching mechanism comprising a movable contact member and means for restraining the same in normal position, of a tripping member for actuating said restraining means, a rotatable member, an actuating member carried by said rotatable member for resetting said movable contact member, and a member disposed within said rotatable member and movable longitudinally independently thereof for actuating said tripping member.

2. The combination with switching mechanism comprising a movable contact member and means for restraining the same in normal position, of a tripping member for actuating said restraining means, a rotatable member, an actuating member carried by said rotatable member for resetting said movable contact member, and a member disposed within said rotatable member and movable axially independently thereof to actuate said tripping member.

3. The combination with switching mechanism comprising a movable contact member and means for restraining the same in normal position, of a tripping member for actuating said restraining means, a rotary shaft having an axial bore, an actuating member secured to said shaft for resetting said movable contact member, and a member for actuating said tripping member movable longitudinally of said bore independently of said actuating member.

4. The combination with switching mechanism comprising a movable contact member and means for restraining the same in normal position, of a tripping member for actuating said restraining means, a rotatable member, an actuating member carried by said rotatable member for resetting said movable contact member, a member disposed within said rotatable member and movable longitudinally independently thereof for actuating said tripping member, and means for preventing longitudinal movement of said actuating member.

5. The combination with switching mechanism comprising a movable contact member and means for restraining the same in normal position, of a tripping member for actuating said restraining means, a rotary shaft having an axial bore, an actuating member secured to said shaft for resetting said movable contact member, a member for actuating said tripping member movable

- longitudinally of said bore independently of said actuating member, and means for preventing longitudinal movement of said actuating member.
6. The combination with switching mechanism comprising a movable contact member and means for restraining the same in normal position, of a pivoted tripping member for actuating said restraining means, a rotatable member, an actuating member carried by said rotatable member for resetting said movable contact member, and a member disposed within said rotatable member and movable longitudinally independently thereof for actuating said tripping member.
7. The combination with switching mechanism comprising a movable contact member and means for restraining the same in normal position, of a pivoted tripping member for actuating said restraining means, a rotary shaft having an axial bore, an actuating member secured to said shaft for resetting said movable contact member, and a member for actuating said tripping member movable longitudinally of said bore independently of said actuating member.
8. The combination with switching mechanism comprising a movable contact member and means for restraining the same in normal position, of a pivoted tripping member for actuating said restraining means, a rotatable member, an actuating member carried by said rotatable member for resetting said movable contact member, a member disposed within said rotatable member and movable longitudinally independently thereof for actuating said tripping member, and means for preventing longitudinal movement of said actuating member.
9. The combination with switching mechanism comprising a movable contact member and means for restraining the same in normal position, of a rotatable member, an actuator carried and rotatable by said rotatable member for resetting said contact member, and a member disposed within said rotatable member and movable longitudinally independently thereof for actuating said tripping member.
10. The combination with switching mechanism comprising a movable contact member and means for restraining the same in normal position, of a rotatable member, an actuator carried and rotatable by said rotatable member for resetting said contact member, a member disposed within said rotatable member and movable longitudinally independently thereof for actuating said restraining means, and means preventing longitudinal movement of said actuator.
11. The combination with switching mechanism comprising a movable contact member and means for restraining the same in normal position, of a support movable with respect to said switching mechanism, a rotatable member carried by said support, an actuator detached from said contact member and carried and rotatable by said rotatable member for resetting said contact member, a member disposed within said rotatable member and movable longitudinally independently thereof for actuating said restraining means, and a rotatable member carried by said support for actuating said tripping member.
12. The combination with switching mechanism comprising a movable contact member and means for restraining the same in normal position, of a support movable with respect to said switching mechanism, a rotatable member carried by said support, an actuator separate from said tripping member carried and rotatable by said rotatable member for resetting said contact member, and a member disposed within said rotatable member and movable longitudinally independently thereof for actuating said tripping member.
13. The combination with switching mechanism comprising a movable contact member and means for restraining the same in normal position, of a tripping member, a rotatable member, an actuator separate from said tripping member carried and rotatable by said rotatable member for resetting said contact member, a member disposed within said rotatable member and movable longitudinally independently thereof for actuating said tripping member, and means for preventing longitudinal movement of said actuator.
14. The combination with switching mechanism comprising a movable contact member and means for restraining the same in normal position, of a support movable with respect to said switching mechanism, a rotatable member carried by said support, an actuator detached from said contact member and carried and rotatable by said rotatable member for resetting said contact member, and a member disposed within said rotatable member and movable longitudinally independently thereof for actuating said restraining means.
15. The combination with switching mechanism comprising a movable contact member and means for restraining the same in normal position, of a support movable with respect to said switching mechanism, a rotatable member carried by said support, an actuator detached from said contact member and carried and rotatable by said rotatable member for resetting said contact member, a member disposed within said rotatable member and movable longitudinally independently thereof for actuating said restraining means, and means preventing longitudinal movement of said actuator.
16. The combination with switching mechanism comprising a movable contact member and means for restraining the same in normal position, of a support movable with respect to said switching mechanism, a tripping member carried by said support in detached relation to said restraining means, a rotatable member carried by said support, and means for preventing longitudinal movement of said actuator.

an actuator detached from said contact member and carried and rotatable by said rotatable member, and a member disposed within said rotatable member and movable longitudinally independently thereof for actuating said tripping member to actuate said restraining means.

17. The combination with switching mechanism comprising a movable contact member and means for restraining the same in normal position, of a support movable with respect to said switching mechanism, a tripping member carried by said support in detached relation to said restraining means, a rotatable member carried by said support, an actuator detached from said contact member and carried and rotatable by said rotatable member, a member disposed within said rotatable member and movable longitudinally independently thereof for actuating said tripping member to actuate said restraining means, and means for preventing longitudinal movement of said actuator.

18. The combination with switching mechanism comprising a movable contact member and means for restraining the same in normal position, of a support movable with respect to said switching mechanism, a tripping member pivoted to said support in detached relation to said restraining means, a rotatable member carried by said support, an actuator detached from said contact member and carried and rotatable by said rotatable member, and a member disposed within said rotatable member and movable longitudinally independently thereof for actuating said tripping member to actuate said restraining means.

19. The combination with switching mechanism comprising a movable contact member and means for restraining the same in normal position, of a housing enclosing said switching mechanism, a rotatable member carried by said housing, an actuator carried and rotatable by said rotatable member and disposed within said housing in detached relation to said contact member, means on the exterior of said housing for rotating said rotatable member, and a member operable from the exterior of said housing and movable longitudinally within said rotatable member and independently thereof for actuating said restraining means.

20. The combination with switching mechanism comprising a movable contact member and means for restraining the same in normal position, of a housing enclosing said switching mechanism, a rotatable member carried by said housing, an actuator carried and rotatable by said rotatable member and disposed within said housing in detached relation to said contact member, means preventing longitudinal movement of said actuator, means on the exterior of said housing for rotating said rotatable member,

and a member operable from the exterior of said housing and movable longitudinally within said rotatable member and independently thereof for actuating said restraining means.

70

21. The combination with switching mechanism comprising a movable contact member and means for restraining the same in normal position, of a housing enclosing said switching mechanism, a tripping member carried by said housing in detached relation to said restraining means, a rotatable member carried by said housing, an actuator separate from said tripping member disposed within said housing and carried and rotatable by said rotatable member, means on the exterior of said housing for rotating said rotatable member, and a member operable from the exterior of said housing movable longitudinally within said rotatable member independently thereof for actuating said tripping member.

75

22. The combination with switching mechanism comprising a movable contact member and means for restraining the same in normal position, of a housing enclosing said switching mechanism, a tripping member pivoted upon said housing in detached relation to said restraining means, a rotatable member carried by said housing, an actuator separate from said tripping member disposed within said housing and carried and rotatable by said rotatable member, means on the exterior of said housing for rotating said rotatable member, and a member operable from the exterior of said housing movable longitudinally within said rotatable member independently thereof for actuating said tripping member.

80

23. The combination with switching mechanism comprising a movable contact member and means for restraining the same in normal position, of a housing enclosing said switching mechanism, a tripping member carried by said housing in detached relation to said restraining means, a rotatable member carried by said housing, an actuator separate from said tripping member disposed within said housing and carried and rotatable by said rotatable member, means preventing longitudinal movement of said actuator, means on the exterior of said housing for rotating said rotatable member, and a member operable from the exterior of said housing movable longitudinally within said rotatable member independently thereof for actuating said tripping member.

85

24. The combination with switching mechanism comprising a movable contact member and means for restraining the same in normal position, of a tripping member tending to move in a direction to actuate said restraining means, a member movable with respect to said switching mechanism, and a member carried by said last named member

and disposed in the path of travel of said tripping member to prevent its movement in direction to actuate said restraining means.

25. The combination with switching mechanism comprising a movable contact member and means for restraining the same in normal position, of a tripping member tending to move in a direction to actuate said restraining means, a member movable with respect to said switching mechanism, and a member carried by said last named member and disposed in the path of travel of said tripping member to prevent its movement in direction to actuate said restraining means, said tripping member when freed by movement of said movable member holding said restraining means in inoperative position preventing restraint of said contact member until return of said movable member to normal position.

26. The combination with switching mechanism comprising a movable contact member and means for restraining the same in normal position, of a tripping member tending to move in a direction to actuate said restraining means, a housing enclosing said switching mechanism and tripping member, and a member carried by and movable with a wall of said housing to and from position 25 in which it prevents movement of said tripping member in direction to actuate said restraining means.

35 27. The combination with switching mechanism comprising a movable contact member and means for restraining the same in normal position, of a tripping member tending to move in a direction to actuate said restraining means, a housing enclosing said switching mechanism and tripping member, and a member carried by and movable with a wall of said housing to and from position in which it prevents movement of said tripping member in direction to actuate said restraining means, said tripping member when freed by movement of said housing wall holding said restraining means in inoperative position preventing restraint of said contact member until return of said housing wall to normal position.

50 28. The combination with switching mechanism comprising a movable contact member and means for restraining the same in normal position, of a tripping member tending to move in a direction to actuate said restraining means, a housing enclosing said switching mechanism and tripping member, a member carried by and movable with a wall of said housing to and from position in which it prevents movement of said tripping member in direction to actuate said restraining means, and an actuator carried by said housing for resetting said contact member when said tripping member is withheld from actuating said restraining means.

55 29. The combination with switching mech-

anism comprising a movable contact member and means for restraining the same in normal position, of a tripping member tending to move in a direction to actuate said restraining means, a housing enclosing said switching mechanism and tripping member, a member carried by and movable with a wall of said housing to and from position in which it prevents movement of said tripping member in direction to actuate said restraining means, said tripping member when freed by movement of said housing wall holding said restraining means in inoperative position preventing restraint of said contact member until return of said housing wall to normal position, and an actuator carried by said housing for resetting said contact member when said tripping member is withheld from actuating said restraining means.

30. The combination with switching mechanism comprising a movable contact member and means for restraining the same in normal position, of a tripping member tending to move in a direction to actuate said restraining means, a housing enclosing said switching mechanism and tripping member, a member carried by and movable with a wall of said housing to and from position in which it prevents movement of said tripping member in direction to actuate said restraining means, and a second tripping member carried by said housing wall and operable from the exterior thereof for actuating said restraining means when said first named tripping member is withheld from actuating said restraining means. 90 95 100

31. The combination with a support, of a base carried by and movable with respect thereto, switching mechanism carried by said base and comprising a movable contact member and means for restraining it in normal position, a housing enclosing said switching mechanism carried by said support and movable with respect to said base, a tripping member movable in a direction to actuate said restraining means to trip said contact member, a member pivoted on said base, a spring engaging said pivoted member and adapted to control said tripping member through said pivoted member, and a member carried by and movable with said housing normally disposed in the path of said pivoted member to prevent actuation of said tripping member until movement of said housing with respect to said base. 105 110 115 120

32. The combination with a base, of switching mechanism carried thereby comprising a movable contact member and means for restraining it in normal position, 125 a housing enclosing said switching mechanism, a tripping member adapted to control said restraining means to trip said contact member, a member pivoted on said base, a spring engaging said pivoted member and 130

controlling said tripping member there-through, and a member carried by and movable with a wall of said housing restraining said pivoted member against movement effecting tripping of said contact member until movement of said housing wall with respect to said base.

33. The combination with a base, of switching mechanism on said base comprising a movable contact member and means for restraining it in normal position, a lever pivoted on said base, a spring operating upon said lever to move it in a direction to operate said restraining means, a member movable with respect to said base, and a member carried by said last named member and coacting with said pivoted lever in opposition to said spring to prevent movement of said lever in a direction to actuate said restraining means.

34. The combination with a base, of switching mechanism on said base comprising a movable contact member and means for restraining it in normal position, a lever pivoted on said base, a spring operating upon said lever to move it in a direction to operate said restraining means, a member movable with respect to said base, a member carried by said last named member and co-acting with said pivoted lever in opposition to said spring to prevent movement of said lever in a direction to actuate said restraining means, and manually operable means detachably engaging with said member which is movable with respect to said switching mechanism for holding said member in position in opposition to said spring.

35. The combination with a base, of switching mechanism on said base comprising a movable contact member and means for restraining it in normal position, a lever pivoted on said base, a spring operating upon said lever to move it in a direction to operate said restraining means, a housing enclosing said switching mechanism and movable with respect to said base, and a member carried by said housing and co-acting with said pivoted lever in opposition to said spring to prevent movement of said lever in a direction to actuate said restraining means.

36. The combination with a base, of switching mechanism on said base comprising a movable contact member and means for restraining it in normal position, a lever pivoted on said base, a spring operating upon said lever to move it in a direction to operate said restraining means, a housing enclosing said switching mechanism and movable with respect to said base, a member carried by said housing and co-acting with said pivoted lever in opposition to said spring to prevent movement of said lever in a direction to actuate said restraining means, and manually operated means engaging with

said housing for holding said housing in position in opposition to said spring.

37. The combination with switching mechanism comprising a movable contact member and means for restraining the same in normal position, of a tripping member, a spring operating upon said tripping member to move it in a direction to actuate said restraining means, a member movable with respect to said switching mechanism, and a member carried by said last named member and engaging said tripping member to hold it in opposition to said spring in position to prevent movement of said tripping member in a direction to actuate said restraining means, and manually operable means detachably engaging with said member which is movable with respect to said switching mechanism for holding said member in position in opposition to said spring.

38. The combination with switching mechanism comprising a movable contact member and means for restraining the same in normal position, of a tripping member, a spring operating upon said tripping member to move it in a direction to actuate said restraining means, a housing enclosing said switching mechanism, and a member carried by said housing to engage said tripping member and hold it in opposition to said spring to prevent actuation of said restraining means by said tripping member, and manually operable means detachably engaging said housing for holding it in opposition to said spring.

39. The combination with a fixed housing, of a base thereon, switching mechanism carried by said base and comprising a movable contact member and means for restraining it in normal position, a second housing pivoted upon said housing independently of said base, a tripping member, a spring operating upon said tripping member to move it in a direction to actuate said restraining means, and a member carried by said second housing and adapted to hold said tripping member in opposition to said spring to prevent actuation of said restraining means by said tripping member.

40. The combination with a fixed housing, of a base thereon, switching mechanism carried by said base and comprising a movable contact member and means for restraining it in normal position, a second housing pivoted upon said housing independently of said base, a tripping member, a spring operating upon said tripping member to move it in a direction to actuate said restraining means, a member carried by said second housing and holding said tripping member in opposition to said spring to prevent actuation of said restraining means by said tripping member, and members carried respectively by said housings and de-

tachably engaging each other to hold said second housing in operative relation with respect to said base in opposition to said spring.

- 5 41. The combination with a fixed housing, of a base pivoted thereon, switching mechanism carried by said base and comprising a movable contact member and means for restraining it in normal position, 10 a second housing pivoted upon said housing independently of said base, an abutment on said second housing engaging said base to hold it in predetermined position with respect to said first named housing, a tripping 15 member, a spring operating upon said tripping member to move it in a direction to actuate said restraining means, and a member carried by said second housing and holding said tripping member in opposition to 20 said spring to prevent actuation of said restraining means by said tripping member. 42. The combination with a fixed housing, of a base pivoted thereon, switching mechanism carried by said base and comprising a movable contact member and means for restraining it in normal position, 25 a second housing pivoted upon said housing independently of said base, an abutment on said second housing engaging said base to hold it in predetermined position with respect to said first named housing, a tripping member, a spring operating upon said tripping member to move it in a direction to

actuate said restraining means, a member carried by said second housing and holding 35 said tripping member in opposition to said spring to prevent actuation of said restraining means by said tripping member, and members carried respectively by said housings and detachably engaging each other to 40 hold said second housing in position in which said abutment holds said base in said predetermined position and in which said member carried by said second housing holds said tripping member in opposition to said 45 spring to prevent actuation of said restraining means by said tripping member.

43. The combination with a plurality of switching mechanisms each comprising a movable contact member and means for restraining it in normal position, of a bar common to said switching mechanisms for actuating their said restraining means, a tripping member, a spring operating on said tripping member and tending to move it to 50 actuate said bar to actuate said restraining means, a member movable with respect to said switching mechanisms, and a member carried by said last named member holding said tripping member in opposition to said 55 spring.

In testimony whereof, I have hereunto affixed my signature this 15th day of February, 1923.

WILLIAM M. SCOTT.
